UNITED STATES PATENT OFFICE.

GEORGE W. SHIEBLER, OF BROOKLYN, NEW YORK.

DESIGN FOR A SPOON.

SPECIFICATION forming part of Design No. 22,363, dated April 25, 1893.

Application filed March 8, 1893. Serial No. 465,185. Term of patent 7 years.

To all whom it may concern:

Be it known that I, GEORGE W. SHIEBLER, a citizen of the United States, residing at Brooklyn, in the county of Kings and State of New York, have invented a new Design 5 for Spoons, of which the following is a specification.

The leading feature of the said design is the relief ornamentation on the handle and 10 in the bowl of the spoon. On the face of the spoon Figure 1 are the female head and miter *a*, and leaf ornaments *b*, in relief, also the representation of a globe *c*, a lamp *d*, and books *e*, and two sculls *f*, are represented as tied to-

gether at *g*, and there is a female figure at *h*. 15 in the bowl and also the representation of lawn tennis at *i*. On the reverse of the handle and spoon are the scroll ornaments shown in Fig. 2.

I claim—

The design for a spoon substantially as described and shown.

Signed by me this 6th day of March, 1893.

GEO. W. SHIEBLER.
